J. E. FARRELL

VAULT

Filed July 17, 1922

James E. Farrell
Inventor
By *W. H. Kress*
Attorney

UNITED STATES PATENT OFFICE.

JAMES E. FARRELL, OF THROOP, PENNSYLVANIA.

VAULT.

Application filed July 17, 1922. Serial No. 575,529.

To all whom it may concern:

Be it known that I, JAMES E. FARRELL, citizen of the United States, residing at Throop, in the county of Lackawanna and State of Pennsylvania, have invented certain new and useful Improvements in Vaults, of which the following is a specification.

This invention relates to certain new and useful improvements in vaults, and the primary object thereof is to provide a vault structure which is of strong and rigid construction and which has improved means for excluding air and moisture.

A further object of the invention is to provide a structure which is composed of nested inner and outer members which are rigidly connected by an interposed plastic filler, the latter being interlocked with each of the members and serving to afford an insulation about the inner member to prevent the ingress thereto of air, water or moisture.

A still further object of the invention is to provide a vault which has means for enabling air to be exhausted from the interior of the inner or casket-holding member so as to create a vacuum within the inner member.

The invention has still further and other objects which will be later set forth and manifested in the course of the following description.

In the drawings:

Figure 1, is a top plan view, partly broken away.

Figure 2, is a section on line 2—2 of Figure 1.

In proceeding in accordance with the present invention, an outer member is employed having a bottom 1, sides 2, and ends 3 and a top 4. The inner member is located within the outer member and is formed to have a bottom 5, sides 6, ends 7 and a top 8. The inner member is of a size to receive the casket and is spaced at its bottom, sides, ends and top from the corresponding parts of the outer member. The inner faces of the sides and ends of the outer member are formed with dove-tail grooves 9 and the outer faces of the sides and ends of the inner member are formed with similar dovetail grooves 10. The grooves are all vertically disposed and are, with the spaces existing between the two

members, filled with a binder 11 which may be liquid tar or asphalt or any other suitable composition which can be poured into place and which solidifies or hardens so as to rigidly connect the two members, and at the same time acts as an insulation to exclude air and moisture from the inner member. By reason of the dovetail grooves, a more efficient and positive connection is formed between the vertical walls of the two members, resulting in a strong and rigid structure.

For the purpose of allowing air to be exhausted from the inner member a check valve 12 is carried by the top 8 of the inner member and projects upwardly thereabove and into an opening 13 formed in the top 4 of the outer member. The opening 13 is of greater diameter than that of the valve 12 so as to allow suitable connection to be made with the valve and with an air exhaust pump.

In operation, the binder is poured in the spaces between the two members up to the lines 14 of Figure 2 and the vault then placed in its desired position or location ready for the reception of the casket. After the casket has been placed within the inner member, the top 8 is placed in position and an added amount of the binder is supplied to completely enclose the cover 8, following which the top 4 is positioned. After the binder hardens or solidifies, connection is made between the air exhaust pump and the valve and a vacuum created in the inner member. The opening 13 is then filled with a further quantity of the binder, so as to seal the check valve. The binder thus acts to not only connect the two members and to provide insulation against the ingress of moisture, but also acts to afford an air-tight seal not only for the inner member, but also for the valve, thus having a dual function.

The two members may be made of wood or any other suitable material.

What is claimed is:

In a vault, an outer member, an inner member therein having its upper end disposed below the upper end of the outer member, a top for the inner member having an opening, a check valve having a casing projecting at its lower end into said open-

ing, a top for the outer member having an opening in register with the upper end of the casing of the check valve and being of slightly greater diameter than the latter so as to enable a connection from a pump to be made with the check valve casing through said opening of the top of the outer member, and a binder between the members ex- tending over the top of the inner member and upwardly into and completely filling 10 the opening of the top of the outer member and disposed substantially flush with the upper face of the top of the outer member. In testimony whereof I affix my signature.

JAMES E. FARRELL.
